FLOWER HOLDER

Walter H. McCallum, San Francisco, and Roderick I. McLellan, Colma, Calif., assignors to E. W. McLellan Co., Colma, Calif., a corporation of California

Application November 10, 1947, Serial No. 142,410

Term of patent 14 years

(Cl. D35—3)

To all whom it may concern:

Be it known that we, Walter H. McCallum and Roderick I. McLellan, citizens of the United States, residing at 1012 Shrader Street, San Francisco, California, and Box 289, Colma, California, respectively, have invented a new, original, and ornamental Design for a Flower Holder, of which the following is a specification, reference being had to the accompanying drawing, forming a part hereof.

Fig. 1 is a perspective view of a flower holder, showing our new design.

Fig. 2 is a rear elevational view of the holder of Fig. 1.

Fig. 3 is a side elevational view of the holder of Figs. 1 and 2.

We claim:

The ornamental design for a flower holder, as shown.

WALTER H. McCALLUM.
RODERICK I. MCLELLAN.
